FIG 5

FIG 3

INVENTOR
CHARLES M. McCARTHY
BY HIS ATTORNEY

James F. Williamson

UNITED STATES PATENT OFFICE.

CHARLES M. McCARTHY, OF MINNEAPOLIS, MINNESOTA.

WIRE-CLOTH-DISPLAY ROLL RACK.

Application filed September 14, 1921. Serial No. 500,598.

To all whom it may concern:

Be it known that I, CHARLES M. McCARTHY, a citizen of the United States, residing at Minneapolis, in the county of Hennepin and State of Minnesota, have invented certain new and useful Improvements in Wire-Cloth-Display Roll Racks; and I do hereby declare the following to be a full, clear, and exact description of the invention, such as will enable others skilled in the art to which it appertains to make and use the same.

This invention relates to a display rack, and particularly to such a rack designed to hold rolls of screen or wire cloth.

It is an object of this invention to provide a rack on which the rolls of cloth are supported in superposed relation, the width of the cloth and rolls being widest at the bottom of the rack and decreasing toward the upper portion thereof.

It is a further object of the invention to provide the various rolls of cloth with tensioning means so that the cloth can be drawn therefrom without unwinding too rapidly.

It is still another object of the invention to provide the rack with a cutting table provided with pressing means over which the cloth from the various rolls can be drawn and cut into the desired lengths.

These and other objects and advantages of the invention will be apparent from the following description made in connection with the accompanying drawings in which like reference characters refer to the same parts throughout the different views and in which—

Fig. 1 is a view in side elevation of the rack;

Fig. 2 is a plan view thereof;

Fig. 3 is a view in end elevation of the rack, as seen from the right of Fig. 1;

Fig. 4 is a view on an enlarged scale showing the tension devices; and

Fig. 5 is a fragmentary view of a portion of the device.

Referring to the drawings, the device comprises a frame having spaced base members 1 formed preferably of standard angle iron which are provided with caster supporting rollers 2. These supporting rollers will preferably be of the univer-

sal type in which the roller can swing about a central axis. Rising from one side of the base are spaced vertical members 3 also preferably formed of angle iron and these members are connected at the top to a rectangular frame of angle members 4. The width of the top frame is considerably less than the width of the base frame and these frames are connected at the other side by spaced angle members 5 extending upwardly in an inclined direction. One side of the angle members 3 is provided with holes to form the bearings for the supporting shafts or journals 6 of the rollers 7 upon which the screen or wire cloth is wound. The shafts 6 extend through the rollers 7 and are journaled at their other ends in plates 8 of angular formation, which are riveted, or otherwise secured to one side of the angle members 5. It will be seen from Fig. 1 that the longest rollers 7 are near the bottom of the supporting rack and decrease in length toward the top thereof.

The base frame is provided with suitable cross members connecting the angles 1 and a pair of contacting angle members 9 extend from said cross members to similar cross members extending between the members 4 of the top frame. Pivoted to the members 9 in substantial alinement with the top of the throw and extending outward therefrom are bar members 10 formed with a curved portion 10^a at their outer ends which is adapted to overlie and contact with the top of the cloth material on the rolls 7. The members 10 are yieldingly held against the said rolls of cloth by springs 11 secured thereto and extending downwardly to the members 9 to which their other ends are also secured.

At each side of the frame a cutting table is provided comprising spaced members 12 preferably of angle formation, which are pivoted at their inner ends to the vertical members 3 and to plates secured to the vertical members 5. These members 12 have secured thereon near their outer ends, the table proper 13, preferably made of wood. This table has a groove 13^a extending transversely thereacross at approximately its central portion and a presser member 14 in the form of a handle lever extends across the said

table and is pivoted to lugs upstanding from one end thereof. This member 14 carries on its undersurface a corrugated or zigzag piece of spring wire or sheet metal 5 which is suitably secured thereto and adapted to be pressed down on the screen cloth to hold the same in a flat condition on the table. The members 12 are supported by pairs of links 13 pivoted thereto 10 and to the vertical members of the frame having their ends overlapping. A bolt or rivet member extends through a hole in one of the links and through a slot in the other link and one of the links is also provided 15 with a stop member 14 overlying the other link. When the table is extended, as shown at the left of Fig. 3, these links are arranged in alinement to form a toggle to support the table but the same can be folded 20 inwardly toward the frame and the table swung down parallel to the frame, as shown at the right of Fig. 3, the members 12 swinging about their pivot connections with the frame.

25 Secured to one side of the angle members 3 is a holder member 15 adapted to receive a tape line casing of the spring type, the tape line 16 of which can be drawn outwardly across the table, as shown in Fig. 3, 30 so that the length of the screen to be cut can be quickly and conveniently measured.

The rolls of screen will be supported, as described, and when it is desired to cut off a link from the roll the loose end of the 35 screen will be drawn down under the pressing device 14 and drawn out to the required length, the same being quickly and easily measured by the tape line 16. The screen can be maintained in flat condition by the 40 presser device and when the required length has been drawn out, the pressing device will be pressed firmly on the screen to hold the same in flat condition on the table and the screen can then be cut by a knife blade, as 45 illustrated in Fig. 1, the blade, preferably being moved along in the groove 13^a. The tension device on the rolls of screen will prevent the same from revolving unduly from their acquired momentum and thus un- 50 rolling an undesirable amount of screen at the roll. The rack can be quickly moved to any desired part of the store or warehouse and the cutting tables thereon can be quickly raised and collapsed, as desired.

55 From the above description it is seen that applicant has provided a simple and efficient supporting rack for screen cloth of different character and length and from which the screen can be quickly dispensed. 60 It is well known that such screen cloth is bulky and awkward to handle when the rolls are loose and such rolls have usually merely been stood about the store. With the use of the rack the rolls are off the 65 floor and out of the way and can be very

easily and conveniently handled. The rack is easily and cheaply constructed from standard structural material and has no parts which are complicated or liable to give any trouble.

70 It will, of course, be understood that various changes may be made in the form, details and arrangement of the device without departing from the scope of applicant's invention, which, generally stated, consists in the matter shown and described and set forth in the appended claims.

75 What is claimed is:

1. A device for supporting and dispensing 80 rolled sheet material having in combination, a frame comprising spaced vertical members diverging toward their lower ends, rolls extending between and having their ends journaled in said vertical members adapted to hold rolls of sheet material carried thereon, a vertical member at one side of and intermediate of said members, and tension devices for said rolls movably mounted on said last mentioned member and extending over and engaging the tops of 85 said rolls of material, springs holding said tension devices in engagement with said rolls whereby said frame is thus unobstructed at its outer side so that the material of said rolls can be unrolled therefrom and carried outwardly and downwardly from said frame.

90 2. A device for holding and dispensing 95 rolls of sheet material comprising a base frame, a central standard extending vertically therefrom, vertical frames at each side of said base having a vertical side and another side diverging from said side toward its bottom, rolls extending between 100 and journaled in said sides and adapted to support rolls of sheet material, arms pivoted to said standard and projecting at each side thereof and adapted to contact the tops of said rolls, spring means holding said arms down on said rolls whereby the rolls are unobstructed at the outer sides of said frame so that said material can be unrolled 105 therefrom, and means forming a flat surface 110 for supporting said unrolled material.

115 3. A wire screen rack having in combination, a frame having upwardly converging side members, rolls journaled in and extending between said side members adapted to carry sheet material, said side members having vertical surfaces parallel with the ends of said rolls adapted to hold the rolls against excessive longitudinal movement and to facilitate the unrolling of the sheet material therefrom, and means retarding 120 the rotation of said rolls contacting the tops thereof whereby the sheet material may be unrolled outwardly at the side of said frame from a roll without removing said roll from the frame.

125 4. A wire screen rack having in combina- 130

tion, a frame having a vertical side and a side inclined toward the upper end thereof, said latter side having spaced vertical plates secured thereto, rolls of different lengths extending between said plates and said vertical side and journaled therein and adapted to carry sheet material, spring pressed

means extending over said rolls to retard rotation thereof, said sheet material being adapted to be pulled outwardly and unrolled from any of said rolls at the sides of the frame. 10

In testimony whereof I affix my signature.
CHARLES M. McCARTHY.
